(57) CLAIM

The ornamental design for a floor panel for automobile, as shown and described.

DESCRIPTION

FIG. 1 is a perspective view of a floor panel for automobile according to the present invention.

FIG. 2 is a front view of the floor panel for automobile of FIG. 1.

FIG. 3 is a rear view of the floor panel for automobile of FIG. 1.

FIG. 4 is a left side view of the floor panel for automobile of FIG. 1.

FIG. 5 is a right side view of the floor panel for automobile of FIG. 1.

FIG. 6 is a top view of the floor panel for automobile of FIG. 1; and,

FIG. 7 is a bottom view of the floor panel for automobile of FIG. 1.

The broken lines and the lightened shading within, illustrate portions of the floor panel for automobile which form no part of the claimed design.
